CUTTING DEVICE

Harry A. Cumfer, Chicago, Ill., assignor to United States Gypsum Company, Chicago, Ill., a corporation of Illinois

Application December 4, 1935, Serial No. 52,773

9 Claims. (Cl. 164—33)

This invention relates to the manufacture of covering elements and more especially to the production of roofing elements intended to simulate a plurality of shingles or similar roofing elements. 5 The invention particularly relates to producing, from sheets of fabric impregnated and coated with bituminous materials, covering elements in which the units are simulated by tabs upon the element separated by spaces or cut-outs 10 formed by removal from the sheet of a portion thereof.

Roofing strips intended to be laid in courses with the length of the strip in the coursewise direction and having formed upon one lengthwise 15 edge of the strip a plurality of tabs separated by cut-outs heretofore have been proposed in many forms. Such strips have been made by various forms of cutting devices, including the so-called cylinder cutters in which the cutting knives are 20 mounted upon the periphery of a rotor and the sheet is delivered in tangential or peripheral contact with the rotor and in such relation to the blade that when the knife has passed through the point of tangency of the sheet with the rotor the 25 sheet will have been severed by said knife. In this action the motion of the knife in its peripheral movement about the axis of rotation has a component which is in a direction transversely of the surface of the sheet, which effects the 30 cutting of the sheet to sever one portion thereof from the other. The present invention is particularly concerned with cutting cylinders or equivalent devices which are utilized for cutting sheets in this manner.

In the manufacture of shingle strips or other covering units in which slots or cut-outs are formed a problem arises in the removal of the piece of material cut from the sheet in the formation of the slot or cut-out. Especially when 35 sheets of fabric are impregnated or are impregnated and coated with bituminous materials, such as asphalt or other mastic and adhesive saturants and coatings, the removal of the piece of material corresponding to the slot becomes difficult 40 because of the adhesiveness of these saturants and coatings which causes the piece to cling to the cutting device. It becomes necessary to take measures to insure the removal of this piece if damage to the elements being made is not to 45 occur and if proper action of the cutting device is to be secured.

Heretofore it has been suggested to remove this piece of material by forcing the successive pieces inwardly toward the axis of the rotor through 50 channels or vaults formed as by coring in the

body of the rotor, a port being provided leading to a central cored chamber in the rotor or in some cases leading again to the circumference of the rotor at a place peripherally removed from the cutting knife. Such cutting devices, however, 5 have the disadvantage that owing to the adhesive character of the pieces so removed and because of the limited cross-section of the channel the movement through the channel and through the port to clear the rotor of such pieces 10 is interfered with or stopped. When this occurs the process of cutting the elements must be stopped in order to clear the rotor before proceeding.

The invention of the present application provides a positive means for moving the portions or pieces severed by the cutting knife so as to clear this knife of said severed pieces. The invention provides for such removal without interfering with the cutting action of the knife and 15 effects a positive movement of removal of the severed piece after completion of the severing cut. The invention further provides for the positive ejection of the severed piece from the cutting device so that the knife is cleared of contact with the severed pieces before again coming 20 into cutting relation with the sheet. This action of the device of the present invention may be accomplished with materials of different kinds 25 but is especially effective where the pieces which 30 are severed are adhesive because of their being saturated or coated with adhesive materials, as in the manufacture of roofing elements.

While a simple embodiment of the invention is shown in the drawings and is described in the 35 specification, the invention finds application to cutting devices having different forms. It is a feature of the invention, however, that similarly to the embodiment illustrated and described, the invention finds particular application in those 40 devices in which the cutting action proceeds in a continuous manner from the start of the cutting to the completion thereof and especially with concomitant motion of the sheet. This concomitant motion which, in the embodiment 45 illustrated, is that occurring in feeding the sheet tangentially to the peripheral motion of the rotor, is combined with a motion of the knife as stated above, which is transversely of the movement of the sheet or has a component in 50 said transverse direction. In the embodiment illustrated this is accomplished merely by the motion of the knife along the circumference of the circle about the axis upon which the rotor rotates.

In order to effect removal of the severed piece from contact with the knife the device of the invention provides means positioned adjacent the knife and arranged to be moved with respect to the knife in a direction of said transverse movement or of said component. In the illustrated embodiment the movement of said device is transversely of the peripheral extent of the rotor and, therefore, is transversely of the surface of the sheet when the knife is in cutting position. By this motion transversely of the surface of the rotor ejection of the severed piece from the rotor and from contact with the knife is secured and also recession of the means for effecting the ejecting may be accomplished so as to avoid interference with the cutting action of the knife when said knife is in cutting relation to the sheet. The means by which this motion transversely of the periphery of the rotor is accomplished will be more clearly understood, as will be the operation of the device of the invention in the production of covering elements, from the description to follow in connection with the drawings in which

Figure 1 shows in part a longitudinal section and in part an elevation of the device of the invention;

Figure 2 is a section on line 2—2 of Figure 1;

Figure 3 shows an end elevation of the device of the invention; and

Figure 4 is a side view in outline of the same.

In the drawings the rotor 1 is constructed with a body 3 which may be cast or forged in generally cylindrical form and may be provided with a shaft 5 cast integrally therewith and turned concentric with the axis 7 of the cylinder. In the drawings the shaft 5 is shown extending at one side of the rotor, only one-half of the length of the particular rotor illustrated being shown in the drawings. The shaft when mounted in suitable bearings indicated by 8 makes possible the rotating of the rotor upon its axis 7 by any suitable means, as by a spur gear on either or both ends of the shaft and fitting into the driving train of the machine. A sheet of material 10, Fig. 3, may, therefore, be contacted and severed when passed between the rotor 1 and a counter cylinder or anvil roll 9.

In the periphery of the body 3 of the rotor is formed a recess or socket 11 within which may be mounted a block 13 carrying the knife 14. Said knife, as formed in the particular embodiment illustrated, is provided with blades 15 bearing upon the shoulder 16 formed in the block 13. By means of screws 17 passing laterally through the block 13 from each side thereof and having the heads 19 countersunk in the block 13, the knife 14 is held in place in the block 13, the screws being tapped into the blades 15 of the knife 14. The block 13, together with the knife 14, securely held therein as described, may be inserted in and removed from the recess 11. By means of bolts 21 having the heads 23 thereof countersunk in the block 13 and tapped into the body 3 of the rotor the block 13 may be held securely in the recess 11. By removal of the bolts 21 the block 13 may be withdrawn bodily from the recess and thereafter the knife 14 may be removed from the block for the purpose of grinding or replacement.

The body 3 of the rotor also is longitudinally recessed at 25 as shown in the cross-section in Figure 2 to provide a space within which the ejector bar 27 may be arranged, said bar being of such cross-section with respect to the recess

that it may be moved transversely of its length in a direction outwardly and inwardly of the axis 7 of the rotor. As illustrated in Figures 1 and 2, the ejector bar 27 is at the portion of the recess 25 toward the axis 7. Outwardly of the bar 27 may be seen a space between the bar 27 and the bottom face 18 of the block 13. Fastened to the ejector bar 27 by means of bolts 29 tapped in the bar 27 is a block 31 of such cross section as to fit the slotted portion 20 of the block 13 and to pass up between the blades 15 of the knife 14. The dimension of the block 31 outwardly from the bar 27 is such that when the bar 27 is in the recessed position, as shown at the top of Figures 1, 2 and 3, the outer end of the block 31 is inwardly of the cutting edges of the knife 14 so that, as may be seen in Figure 3, the sheet 10 may be cut by the knife 14 without interference of the block 31.

Upon the ends of the ejector bar 27 are mounted rollers 35 fitted to run upon the turned portion 37 of the bar 27. The turned portion 37 of the bar 27 projects beyond the end face 4 of the rotor body 3 so that the roller 35 is exterior to the body 3 of the rotor.

A cam or eccentric plate 40 is formed as a ring with its internal diameter fitting to the shaft 5 and held against the body 3 of the rotor by means of the end of a stationary bearing sleeve or block 41 for the shaft 5, by means of set-screws 42 passing through a flange ring of plate 40 which snugly fits over the end of the said bearing. In the face of the cam plate 40 is formed a cam groove having its outer face 43 parallel to the inner face 44 and of such width between said cam faces and of such depth in the inner face of the cam plate 40 that the cam roller 35 may fit into the groove thus formed in the cam plate 40 with a running clearance when the plate 40 is positioned against the body 3 of the rotor and held in engaging stationary position with the cam roller 35 by the bearing 41 as described.

The cam surfaces 43 and 44, which are shown in dotted line in Figure 3, in the particular embodiment illustrated are cylindrical surfaces parallel to each other. These surfaces, however, are formed eccentric with the axis 7 of the rotor. The cam plate 40 is held from rotation by means of the stationary bearing 41 and the set-screws 42. A bracket 47 is suitably fastened to the frame of the machine or, as shown, to the cam plates 40 at the ends of the rotor by means of the screws 49 tapped in the cam plate 40. Also for each cam plate a pin 50 may be provided. A wiper or stripper 51 of rubber or other flexible or resilient material is secured to the horizontal portion of bracket 47 with its opposite free edge projecting into the path of the ends of the ejector blocks 31, as seen in Figure 3, to brush off any cut out portions having a tendency to stick to the ejector blocks 31. A cam plate 40 may be provided at each end of the rotor 1, each cam plate having a similar groove formed with eccentric cam surfaces 43 and 44 and positioned in like relation as to direction of eccentricity with respect to the axis 7 of the rotor. A similar fastening means, as by the bearing 41 and screws 42, may be used at each end. These means of fastening prevent rotation of the cam plates 40 when the rotor is rotated upon its axis 7 to bring the cutting knives into cutting engagement with the sheet 10 as the sheet moves tangentially to the rotor.

In view of the eccentricity of the cam surfaces 43 and 44 and the engagement of the roller 35

therewith it will now be understood that, as the rotor rotates upon its axis and as the body 3 of the rotor carries the bar 27 and its block 31 around the axis 7, the cam roller 35 will be moved outwardly and inwardly with respect to the axis 7 of the rotor in a complete revolution or rotation upon its axis. Thus the block 31 will be moved outwardly and inwardly within the space between the blades 15 of the knife 14. In a rotation from the position shown in Figure 3 where the upper knife is in cutting engagement with the sheet 10 and the block 31 is withdrawn below the edges of the knife blades 15, the block 31 will be moved outwardly between the blades 15 until at the quarter revolution substantially the outer face 32 of the block 31 may be at the periphery corresponding to the cutting edges of the knife blade 15. In this movement the piece of material which may be retained from the cut just finished between the knife blades 15 has been pushed out between these blades and may fall clear of the rotor. If by the adhesiveness of the saturating or coating materials or for other reason the piece adheres to one or the other knife in the next quarter revolution, a further movement of the block 31 is produced to completely push the severed piece clear of the knife blades 15. If the piece still clings, the brush, wiper or stripper 51 engages and effectually removes it. Thereafter upon further rotation of the rotor the block 31 recedes again between the knife blades 15 and when the blades 15 are about to come into cutting relation with the sheet 10 the face 32 of the block 31 has receded below the edges of these blades so that the cutting may be started and completed without interference by the block 31.

It will be understood that although in the illustrated embodiment the cam surfaces have been shown in the simple form provided by parallel cylindrical surfaces eccentric to the axis of the rotation of the rotor, other forms of cam surfaces may be used to effect a quick ejection or a dwell in the different portions of the revolution. The device illustrated, however, provides an easy motion which is mechanically positive and is effective to move the ejector block between the knife blades and to eject the severed pieces from between the blades. No complicated kinematic motions are involved, and the parts may be readily removed for renewal or repairs. Such removal may be effected by removal of the rotor unit and the bearing as a whole from the machine frame or housing and disassembling the parts. The knives may, of course, be quickly removed without taking out the rotor. The rotor may be provided also with suitable severing knives or blades as indicated in dotted lines in Figure 1, a circumferential knife or blade being indicated at 85 and a longitudinal knife or blade at 89, these being arranged, supported and secured in any desired or usual way.

In Figure 1 in the cam plate 40 is shown a groove 100 cut in the inner face of the plate adjacent the periphery thereof in such position as to be covered by the end of the body 3 of the rotor 1 or by the filler plates 102. This groove preferably is filled with a felt gasket or washer of suitable size and section to bear against the end of the body 3 and the filler plates 102 as the rotor 1 is rotated between the cam plates 40. This gasket serves to prevent dust or grit or other foreign material passing between the body 3 of the rotor 1 and the cam plate 40 and entering the recess 25. Thus the internal reciprocating parts

of the ejector mechanism and the cam roll 35 and the cam surfaces 43 and 44 are protected against damage due to grit and interference with their operation.

Figure 4 shows in diagrammatic outline the complete rotor in which two circumferential rows or sets of knives 15 are shown, that being the usual arrangement, though of course any number of rows or length of rotor may be provided. These knives or associated parts are all of the same construction, arrangement and operation as those specifically shown and described, except that the longitudinal recesses in the rotor and the ejector bars 27 therein suffice for the plurality, in this instance two, of knife assemblies, ejector blocks 31, etc. which are disposed in the same longitudinal line of the rotor. Thus a single ejector bar serves as the operating means for a plurality of ejector blocks.

Various modifications of the invention from that illustrated in the drawings and particularly described may be made without departing from the spirit of the invention. Different forms of mechanism to produce the motion of the ejector block 31 may be utilized which secure the proper time relation between the ejecting action and the cutting of the sheet. All such variations are within the scope of the invention and are intended to be covered by the claims.

Having thus described my invention, I now claim:

1. In a rotary cutting device, a knife blade mounted adjacent the periphery thereof with one of the faces or said blade which form the cutting edge extending in a plane transversely of the peripheral extent of the device, a member adjacent said face of the device arranged for movement in a direction generally parallel to said face of the blade, a cam surface described around the axis of rotation of said device, and a cam roller arranged for rolling upon said cam surface and connected to said member, said parts being arranged so that upon rotation of the device said member is moved outwardly from said axis.

2. In a rotary cutting device, a knife blade mounted adjacent the periphery thereof with one of the faces of said blade which form the cutting edge extending in a plane transversely of the peripheral extent of the device, a member adjacent said face of the device arranged for movement in a direction generally parallel to said face of the blade, a fixed member providing a cam surface described completely around the axis of rotation of said device, means carrying a cam roller and fastened to said member so as to move therewith and formed and arranged to hold said cam roller in contact with said cam surface as said device rotates upon said axis, whereby reciprocal movement of said member in said direction is effected.

3. In a rotary cutting device, a rotor arranged to rotate upon an axis and having a periphery generally concentric with said axis, said rotor being formed to hold a knife having a blade with that face of said blade which, with the bevel face of the blade, forms the cutting edge of the knife in a plane generally transverse to the periphery of the rotor, a ring fixed with respect to said axis of rotation and providing a surface surrounding said axis eccentric to the periphery of said rotor, said rotor providing adjacent said face of the knife blade a slot extending generally parallel to said face, an ejector block movable in said slot in said direction parallel to said

face, a bar fastened to said block and arranged with an end thereof adjacent said eccentric surface and providing an axis substantially parallel to said eccentric surface, and a roller arranged 5 to turn upon said axis provided by said bar and to roll upon said eccentric surface to cause movement of said block outwardly and inwardly in said slot upon rotation of said rotor upon its axis.

4. In a rotary cutting device as in claim 3, 10 means for moving a sheet of material into peripheral cutting contact with said knife when said block is at a point inwardly of said slot to leave the blade free of interference with the cutting, said parts being so arranged that upon outward movement of said block the portion of the 15 sheet severed at said face of the blade is moved out of contact therewith.

5. In a cutting machine of the character described, a movable knife support for cutting co- 20 operation with an anvil, said support having an open end T shaped slot in the surface thereof extending the entire length of said support and providing longitudinal shoulders, a longitudinal ejector bar in said slot below said shoulders and 25 arranged for bodily lateral movement therein, a cutting block on said shoulders, outwardly extending knives on said cutting block substantially in lateral alignment with said bar, an ejector member between said knives and movable with said bar, automatic means for moving 30 said bar during movement of said support and filler blocks closing said T slot between said cutting blocks.

6. A cutting rotor of the character described 35 comprising a cylinder having a plurality of longitudinal radially disposed open end slots extending the entire length of said cylinder, elongated interchangeable longitudinal bars in said slots and spaced from the circumference of said 40 cylinder, means for bodily lateral movement of said bars during a rotation of said cylinder, interchangeable cutter blocks substantially flush with the surface of said cylinder, said blocks having openings therein substantially in radial 45 alignment with said bars, said blocks having outwardly extending cutting edges defining said openings, and ejector members on said bars and substantially filling said openings, and filler blocks closing said slots between said cutter blocks.

50 7. A cutting rotor of the character described comprising a cylinder having a plurality of longitudinal radially disposed open end slots extending the entire length of said cylinder, elongated

interchangeable longitudinal bars in said slots and spaced from the circumference of said cylinder, means for bodily lateral movement of said bars during a rotation of said cylinder, interchangeable cutter blocks substantially flush with the surface of said cylinder, said blocks having openings therein substantially in radial alignment with said bars, said blocks having outwardly extending cutting edges defining said openings, ejector members on said bars and substantially filling said openings, and means accessible from outside said cylinder to enable removal of said ejector blocks through said openings.

8. In a cutting machine of the character described, a cylindrical cutting rotor arranged for 15 continuous rotation for cutting cooperation with an anvil roll, said rotor having longitudinal radially disposed T shaped peripheral slots, the T slots providing longitudinal shoulders, longitudinal bars in said T slots below the said shoulders and arranged for radial reciprocating movement therein, cutting blocks supported on said shoulders and having their outer surfaces forming continuations of the surface of said rotor, said cutting blocks having openings therethrough 20 in radial alignment with said bars, cutters on opposite sides of said openings and extending beyond the surface of said rotor for cutting co-operation with said anvil roll, ejector members removably secured to said bars and substantially 25 filling the opening between said knives and terminating below the cutting edges thereof, and means for reciprocating said bars during a revolution of said rotor to cause said ejector members to eject cut portions from between said knives. 30

9. A cutting device of the character described comprising a rotor having a longitudinal chamber completely therethrough between the axis and the face of the rotor, a normally fixed member substantially sealing each end of said chamber 40 and arranged to permit rotation of said rotor therebetween, a longitudinal ejector bar in said chamber, means to cause automatic lateral reciprocation of said ejector bar during movement of said rotor, said chamber forming a substantial 45 passage past said bar during its movement, spaced cutting knives on said rotor substantially in radial alignment with said bar, an ejector member on said bar and extending through the rotor wall and between said knives, and providing a substantially sealed joint between said member and the rotor wall.

HARRY A. CUMFER.
